SEWER CONSTRUCTION.

Specification of Letters Patent. Patented Sept. 7, 1915.

1,153,158.

Application filed September 30, 1914. Serial No. 864,263.

To all whom it may concern:

Be it known that I, WILLIAM BEALL GRAY, a citizen of the United States, and a resident of Louisville, in the county of Jefferson and State of Kentucky, have invented a new and useful Improvement in Sewer Constructions, of which the following is a specification.

My invention is an improvement in sewer constructions, and has for its object to provide a conduit of molded blocks arranged in such manner as to provide a maximum of resistance to stress in any direction, where in a series of constructor blocks is provided so arranged that they may be laid to form a self-supporting arch or curved wall, and a series of key blocks connected with the constructor blocks in such manner as to lock the constructor blocks against movement in any direction with respect to each other.

In the drawings:—Figure 1 is a perspective view of a portion of an arch constructed in accordance with the invention and with parts in section, and Fig. 2 is a side view 25 of the blocks used in the construction.

In the construction shown in Fig. 1, the conduit which may be a sewer, or any other circular or arched construction is composed of two forms of blocks. The blocks of one form or series are arranged with their side edges adjacent and interlocked, and the said blocks are so constructed and arranged that they may be locked by the blocks of the other form or series. The construction thus 30 consists of a series of building or constructor blocks, and a series of filling or key blocks. Each of the constructor blocks is arched transversely, and for the sake of lightness, and economy the blocks are cellular or 35 chambered. Each of the said blocks is as before stated, arched transversely on an arc of the circle upon which the arch is formed, and each of the said blocks 1 is provided 40 with a lateral extension 2 at each of its side edges, the said extensions extending the full length of the blocks. Thus each of the constructor blocks may be considered as being composed of a body and lateral extensions and the bodies of the blocks in the present 45 instance have two similar longitudinally extending chambers or recesses 3. Each of the extensions 2 is also chambered or recessed longitudinally as indicated at 4, and one of the extensions is provided at its outer side 50 edge with a longitudinally extending groove

5. The other extension 2 is provided at its outer side edge with a longitudinally extending rib 6, the rib registering with the groove of the other extension on the adjacent block. Each extension is grooved longitudinally on its upper face adjacent to the body of the block, as indicated at 7, and the outer side wall of each of the said grooves 7 is undercut as shown at 8. The blocks 1 are laid in courses extending longitudinally of the arch or conduit, the rib 6 of each block fitting within the groove 5 of the preceding block. Cementitious material 9, as for instance, cement or the like, is arranged between the adjacent side edges of the extensions of the constructor blocks for forming a fluid tight joint between the constructor blocks, and it will be evident that after the constructor blocks have been laid there will be a channel between the adjacent courses on the outer face of the arch or conduit. Each of the channels will extend the full length of that portion of the arch or conduit which has been already laid, and the key blocks are arranged within the 80 channels, for filling the same, and for locking the constructor blocks together. It will be evident that the inter-engagement between the grooves 5 and the ribs 6 of the constructor blocks will prevent the lateral 85 movement of the constructor blocks inward with respect to each other. Outward movement however, would unless the ribs 6 and the grooves 5 were of considerable depth cause the disengagement of the ribs from the 90 grooves and permit the blocks to become disengaged or unlocked.

Each of the locking or key blocks 10 is curved transversely on an arc of the circle upon which the arch or conduit is formed, 95 and for the sake of lightness each of the said blocks is channeled or chambered longitudinally as indicated at 11, the chambers or recesses being near the opposite side edges of the blocks. Each of the said key blocks 10 is provided on its under face with a longitudinally extending groove 13, extending the full length of the block, and the side walls 14 of the grooves are undercut as shown. 100 The grooving of the upper faces of the lateral extensions 2 provides at the outer side of the upper face of each extension a longitudinally extending rib 15, the said ribs 15 having the undercut side walls 8. The 105 grooves 13 of the key blocks have a width 110,

approximately equal to the aggregate width of the ribs 15 of the constructor blocks, and the said grooves are adapted to receive the ribs 15 of two adjacent constructor blocks.

- 5 The blocks are of such size that when laid as shown, there will be sufficient clearance between the meeting faces and sides of the blocks, ribs and grooves to receive a sealing medium, and the key blocks are arranged 10 with the undercut ribs 15 of the lateral extensions of the constructor blocks engaging the grooves 13 of the said blocks.

The key blocks cannot move radially outward because of the engagement of the undercut walls of the ribs 15 with the undercut walls of the grooves 13. Neither can the adjacent edges of the constructor blocks move either inward or outward because of the lock formed by the interengaging ribs 20 15 and grooves 13.

The lock provided by the key blocks would be a perfect lock, even were the ribs 6 and the grooves 5 omitted, but by providing these ribs and grooves the construction 25 is more stable. The blocks 1 and 10 may have square ends if desired, that is, they may have their ends plane and perpendicular to the faces; or the blocks 1 and 10 may be arranged as indicated in Fig. 2. Here the constructor blocks 1^a have the lateral extensions 2^a, which are shaped and grooved precisely the same as the extensions 2. Each of the blocks 1^a however, has its ends rabbeted as indicated at 16 and 17, the rabbet 16 being 30 exactly opposite to the rabbet 17. That is, the rabbet 16 is on the inner face of the block and the rabbet 17 on the outer face. When the blocks are rabbeted as shown, the rabbeted face 16 of each block will engage 35 the rabbeted face 17 of the adjacent block. It will be understood that when the constructor blocks have their ends rabbeted, the key blocks may have their ends rabbeted. In addition to the locking function of the 40 key blocks they have a joint breaking function, and every joint is broken. The key blocks break the joints between the constructor blocks, and the constructor blocks and the key blocks break the joints between 45 themselves. When the ends are rabbeted the end joints are also broken. Thus a 50 sewer or conduit constructed with the improved blocks has an inner surface, formed from similar blocks, while the outer surface 55 is formed from two series of blocks.

In practice the distance between the innermost portions of the undercut faces 14 of the grooves 13 may be greater than the distance between the outermost portion of the undercut walls 8 of two adjacent ribs 15, if desired, thus providing a mortar lock.

The improved construction provides a maximum strength against crushing stress and against collapse from pressure at the 60 top of the arc. The arrangement also pro-

vides a maximum strength to resist expanding pressure. Any crushing stress must crush the material of the blocks and the mortar before the interior diameter of the arch or conduit will be changed.

In practice the inner concave face of the blocks 1 and the outer convex faces of the bodies of the said blocks as also the outer convex faces of the blocks 10 are smooth and salt glazed, while the side faces of the extensions 2 and the side faces of the bodies of the blocks 1 above the extensions and the upper faces of the extensions, as well as the bottom and side walls of the grooves 5 and the top and side walls of the ribs 6 as well 80 as the bottoms of the grooves 7 and 13, are roughened or corrugated longitudinally to provide a better hold for the mortar or cement which holds the blocks together.

It will be evident that when the lock between the ribs 15 and the groove 13 is a mortar lock, the key blocks may be laid by placing them directly in the channels between the bodies of the constructor blocks. In sewer construction or in any other construction where branches are necessary, or where other conduits must join the main structure, the openings for the branches and the other connections will be made in the constructor blocks, that is, each branch will 95 have its opening in a constructor block. Thus it is only necessary to cut one block unless the branch is large.

It is obvious that a sectional sewer, that is, a sewer composed of blocks presents advantages over a solid construction molded in place or formed from molded cylindrical sections, in that the blocks are easier handled than the sections and any size sewer may be constructed. In addition the salt glaze provides a water proof surface and an insulating surface as well.

If it is found desirable partitions may be added within the channels of the blocks, especially within the channels 3 when the 110 ends of the said blocks are rabbeted to prevent the mortar from passing into the channels. The partitions would be at the inner ends of the rabbeted portions and would form a mortar bed for preventing displacement of the mortar.

The conduit or arch constructed with the improved blocks has an inner lining of a particular type of blocks and a portion of each of the said blocks extends through to 120 the exterior. When it is desired to cut an opening into the conduit after it has been laid, the opening may be cut through the body of a constructor block.

I claim:

A wall construction, comprising a series of constructor blocks and a series of key blocks, each constructor block consisting of a body and lateral extensions at the inner face of the body and of less thickness than 130

the body, each extension having a longitudinally extending groove on its upper face adjacent to the body and forming a longitudinally extending rib at the outer side edge of the extension, each groove having its outer side wall undercut, the said blocks being laid in courses with their ends and with the outer side edges of the extension abutting, and each key block having on its inner face a longitudinally extending groove having its side wall undercut, the least width of the grooves of the key blocks being greater than

the greatest aggregate width of the ribs of the extensions to permit the direct engagement of the ribs with the extensions, and 15 mortar arranged between the blocks for forming a mortar lock between the ribs and the grooves, the key blocks being laid between the bodies of adjacent courses of constructor blocks.

WILLIAM BEALL GRAY.
